UNITED STATES PATENT OFFICE.

BURNHAM C. STICKNEY, OF ELIZABETH, NEW JERSEY.

TYPE-WRITING MACHINE.

No. 889,344.

Specification of Letters Patent.

Patented June 2, 1908.

Application filed May 24, 1904. Serial No. 209,432.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

The invention relates to type-bar machines of the "visible writing" class, such as top-strike and front-strike machines. In such machines the types are necessarily assembled closely side by side, and in consequence the type-bars are apt to clash; especially when the machine is in rapid operation. To a great extent, such clashing is due to the proximity of type-bars or types which are not only frequently used, but are also often written in immediate succession; there not being sufficient time for one of such types to come to rest before the next is operated, so that the types strike or catch one upon another, which of course is a great objection. As an example, in the "Underwood" style of front strike machine, it is the usual practice to place the type "E" close by the side of the type "D", and since in numerous words these letters are written in immediate succession, considerable interference occurs between these types. The same is true also of the types "C" and "R", and of the types "R" and "F", "N" and "U", "M" and "I", and "O" and "L". This undesirable proximity of frequently combined letters is due to the arrangement of the key-levers, the order of the types in the "type-basket" being the same as that of the levers, and the latter agreeing with the order of the keys. The order of said levers, as well as of the types, is usually as follows: Q A 2 Z W S 3 X E D 4 C R F 5 V T G 6 B Y H 7 N U J 8 M I K 9, O L . P ; , and by reason of this order of the types, it will be seen that clashing is liable to arise between other frequently used letters than those above instanced. Said order of the levers agrees with the order of the keys, which are arranged in four banks and are regularly mounted upon the levers, every fourth lever having a key in the same bank; the rear bank of keys being in the following order: 2 3 4 5 6 7 8 9 , the next bank having the order Q W E R T Y U I O P , the next bank having the order A S D F G H J K L ; , and the front bank having the order Z X C V B N M , . Thus it will be seen that the first key-lever (Q) falls in the next to the

rear key-bank, the second lever (A) in the next to the front bank, the third lever (2) in the rear bank, the fourth lever (Z) in the front bank, and so on in regular alternation. 60 This disposition of the keys and levers gives the advantage that the keys are symmetrically disposed in compact space, with maximum room for their operation; but, as already pointed out, the disadvantage due to 65 the order of the types in the basket is quite serious when the machine is operated at high speed.

The object of the present invention is to overcome the difficulty above explained, 70 without re-arranging the principal keys, and preferably without in the least disturbing the position of the keyboard of any key, to the end that operators of existing machines may, without the necessity of learning a new key- 75 board, operate the machine at high speed with little or no liability of clashing of the type bars.

In the accompanying drawings, in which my improvements are illustrated as applied 80 to an Underwood typewriting machine, Figure 1 is a side elevation of the type actions. Fig. 2 is a diagram illustrating the plan of the types in the basket. Fig. 3 is a plan of the keyboard and the forward ends of the key 85 levers. Fig. 4 illustrates different ways of offsetting the keys from the levers.

In the several views, like parts are identified by like signs.

The keys in the rear bank are designated as 90 20, those in the next forward bank as 21, those in the next bank as 22, and those in the front bank as 23; and the order of the keys in the several banks is the same as that already mentioned. The keys are fixed upon the 95 forward ends of levers 24 of various lengths, fulcrumed upon a rod 25, supported by springs 26, and connected by bell-cranks 27 to type-bars 28, the latter being pivoted upon a curved fulcrum rod 29, and extending forwardly therefrom, and carrying upon their forward ends types 30, each type having both upper case and lower-case letters or characters, as seen at Fig. 2. The type-bars, when operated, swing upwardly and rearwardly, as indicated by the dotted curved line, against a platen (not shown).

As usual in the Underwood machine, the key-levers lie side by side and are evenly spaced, that is, mounted at uniform intervals. The keys are also evenly spaced and symmetrically arranged, in the manner al-

ready detailed. In the preferred form of my invention, however, each key, instead of being centered directly upon its key-lever as heretofore generally practiced, is offset therefrom, to either one side or the other, and some keys are more offset than others (see Fig. 4).

I am aware that keys usually are of sufficient size to overhang the adjoining levers; and I do not claim broadly the idea of having the key overhang more upon one side of the lever than upon the other side thereof. In nearly all instances at Fig. 3, the center of the key falls midway between two levers to one of which the key is attached, so that, in laying out a keyboard, it becomes practicable to attach the key with equal facility to either of two levers, which is an advantage, in that it simplifies the manner of causing the order of the levers (and hence of the types) to be different from the usual order above detailed. The offsetting of the keys from the levers of course makes no difference to the operator, as the relation of the keys *inter se* is unchanged. It should further be pointed out that each of the keys really overhangs four levers, thus making it practicable to attach each key to any one of the four levers thereunder. Therefore by properly attaching the keys, the order of the levers may be considerably varied without varying the order of the keys.

The first key "Q" is set a little to the left of its lever; and the same is true of keys "A" and "2". The fourth lever bears the key "W", the fifth the key "Z", and the sixth the key "S". Thus the first six levers, and hence the first six types, have the order Q A 2 W Z S, instead of the usual order Q A 2 Z W S. The infrequently used type "Z" is therefore interposed between the frequently employed types "W" and "S" which are often written in succession, and hence the liability of clashing of the type-bars "S" and "W" is minimized if not eliminated.

It will be observed that the key "W" can with equal facility be attached to either the fourth or the fifth lever, and that it is attached to the fourth; while it will also be understood that the key "Z" could with equal facility be attached to any of the second, third, fourth and fifth levers, by having the selected lever sufficiently long to reach to the front bank, the fifth being selected so as to bring the "Z" lever between the "W" lever and the "S" lever, thus giving the types the desired order, without the necessity of crossing any connection between the key and the type. It is further obvious that in planning a keyboard according to my invention, it would be practicable to attach the "W" key to any one of the four levers that it overhangs, viz., the third, fourth, fifth and sixth, so that the invention is not limited to the precise order of the levers illustrated. The keys may be offset in various ways; the

forward end of the lever "Z" being illustrated as bent laterally at 31, to bring the key-stem beneath the same portion of the key as in the cases of the keys "Q", "A" and "2", so that the stems may generally be attached in the same manner to all the keys, the latter being of duplicate construction. By similar arrangement, the "X" lever is caused to fall between the "E" and "D" levers, thus avoiding the liability of the clashing of the types "E" and "D", which are not only very frequently employed, but are very often written in succession. The key "4" is also connected to the lever which falls between the levers "C" and "R"; the center of the type "4" falling between the tenth and eleventh levers, but being attached to the twelfth lever; the eleventh lever being "C" and the thirteenth "R". The usual socket 32 of the key "4" may have an offset portion 33 to bear the key (Fig. 4.) In this manner the character lever "5" is caused to fall between the levers "R" and "F", the "6" between "B" and "Y", the "7" between "Y" and "H", the "J" between "N" and "U", the "K" between "M" and "I", and the hyphen mark between "O" and "L". The types have of course a corresponding arrangement, the frequently used types thus being well separated and not apt to clash. In the form of the invention illustrated, the keys which are connected to the outer levers of their respective four-lever groups are "4", "6", "U", "I", "F", "H", "L", "Z" and "X". By "four-lever groups" I mean the four levers beneath each key, to any one of which the key may conveniently be attached. Each of the remaining keys is attached to either one or the other of the middle levers of its group.

At Figs. 2 and 3 it will be seen that the types and levers have the following order, viz.: Q A 2 W Z S 3 E X D C 4 R 5 F V T G B 6 Y 7 H N J U 8 M K I 9, O - L . P.; The keys are variously offset from the levers in a manner such that levers for infrequent letters or characters occur in all cases immediately between levers for frequent letters that are often written in immediate succession. Each of the levers "4", "6", "U", "I", "F", "H", "L", "Z" and "X" has an extra offset key, each such key having its center midway between the levers that adjoin its own lever, as for instance the center of key "4" is midway between levers "D" and "C" which adjoin the lever "4". Four levers ("E", "X", "D" and "C") intervene between the levers of the laterally adjoining keys "3" and "4"; four levers between the levers of the laterally adjoining keys "E" and "R"; five between the levers "5" and "6"; three between the levers "2" and "3" and in other instances, two between the levers "9" and "1", and also between "L" and "1"; and only one between "4" and "5".

"5" or between "6" and "7". This arrangement would be varied in carrying out my invention in different ways.

The keys may be attached in the usual manner, their bottom disks being perforated, however, at one side of the center, for attachment to the sockets 32.

Having thus described my invention, I claim:

- 10 1. In a front strike writing machine, the combination of a system of levers and a system of keys borne upon said levers; said keys being symmetrically arranged in banks, but being variously offset from said levers in a manner such that the order of the keys differs from the order of the levers and so that levers for infrequent letters or characters occur in all cases immediately between levers for frequent letters that are often written in immediate succession; a system of types lying close together substantially in the order of said levers, a system of pivoted bars carrying said types; and means for enabling said levers to operate said type bars.
- 25 2. In a front strike writing machine, the combination of a system of levers lying side by side and spaced with substantial uniformity; banks of keys fixed upon said levers, the keys in the several banks being arranged at substantially uniform intervals, but being generally offset from said levers, some being offset to one side and others to the other side of their levers, in a manner such that the order of the keys differs from the order of the levers and so that levers for infrequent letters or characters generally occur immediately between levers for frequent letters that are often written in immediate succession; a system of types lying close together substantially in the order of said levers; a system of pivoted bars carrying said types; and means for enabling said levers to operate said type bars.
- 35 3. In a typewriting machine, the combination of a system of keys regularly disposed in four banks; the keys in the rear bank having substantially the order 2 3 4 5 6 7 8 9, the keys in the next bank having substantially the order Q W E R T Y U I O P, the keys in the next bank having substantially the order A S D F G H J K L : , and the keys in the front bank having substantially the order Z X C V B N M , . ; levers bearing said keys and having substantially the order Q A 2 W Z S 3 E X D C 4 R 5 F V T G B 6 Y 7 H N J U 8 M K 1 9, O - L . P : ; said keys being variously offset from said levers to effect the specified difference between the order of the keys and the order of the levers; a system of types lying closely together and having substantially the same order as said levers; bars upon which the types are carried; and connections from the levers to the type bars.
- 60 4. In a typewriting machine, the combination with a system of levers mounted side by side at substantially uniform intervals, of a system of keys arranged in banks and fixed upon said levers and offset therefrom in such a manner that the order of the keys differs from the order of the levers; said keys generally being offset from the levers, to such an extent that the centers of the keys fall midway between the levers, and several of the keys having an extra offset, each of the latter keys having its center midway between the levers that adjoin its own lever; a system of types lying closely together and having substantially the same order as said levers; bars upon which the types are carried; and connections from the levers to the type bars.
- 75 5. In a typewriting machine, the combination with a system of levers mounted side by side, of a system of keys arranged in four banks and fixed upon said levers but offset variously therefrom in such a manner that the order of the keys differs from the order of the levers and so that in some instances less than three and in other instances more than three levers intervene between the levers of adjoining keys in the same bank; a system of types lying closely together and having substantially the same order as said levers; bars upon which the types are carried; and connections from the levers to the type bars.
- 85 6. In a typewriting machine; the combination with a system of levers mounted side by side, of a system of keys arranged in four banks and borne upon said levers but offset variously therefrom in opposite directions in such a manner that the order of the keys differs from the order of the levers in some cases one, and in other instances two, in still other instances three, and in still other instances four levers intervene between the levers of laterally adjoining keys; a system of types lying closely together and having substantially the same order as said levers; bars upon which the types are carried; and connections from the levers to the type bars.
- 90 7. In a front strike writing machine, the combination of a system of levers and a system of keys borne upon said levers; said keys being symmetrically arranged in banks, and the keys in each bank being variously offset in different directions from their respective levers, in such a manner that the order of the keys differs from the order of the levers and so that levers for infrequent letters or characters generally occur immediately between levers for frequent letters that are often written in immediate succession; a system of types lying close together substantially in the order of said levers; a system of pivoted bars carrying said types; and means for enabling said levers to operate said type bars.
- 105 8. In a typewriting machine, the combination with keys extending in the usual diagonal rows upon the keyboard, of types having

a different order from the keys, and levers upon which the keys are mounted in offset relation in such a manner that the order of the keys differs from the order of the levers.

5 9. In a typewriting machine, the combination of two levers placed side by side, keys offset in opposite directions from said levers to make the order of the keys the reverse of the order of the levers; and type-bars set 10 close together and having the same order as the levers and connected thereto.

10 10. In a typewriting machine, the combination of two levers placed side by side, keys offset in opposite directions from said levers to make the order of the keys the reverse of the order of the levers, said keys mounted 15 one forward of the other upon the levers; and type-bars set close together and having the same order as the levers and connected 20 thereto.

11. In a typewriting machine, the combination of two levers placed side by side, keys offset in opposite directions from said levers to make the order of the keys the reverse of 25 the order of the levers; the levers upon both sides of said levers having keys offset therefrom to compensate for the offsetting of the first-mentioned keys and conduce to the symmetry of the keyboard; and type-bars 30 set close together and having the same order as the levers and connected thereto.

12. In a typewriting machine, the combination of two levers placed side by side, keys offset in opposite directions from said levers, 35 one key immediately behind the other, a third lever at one side of said levers and having a key offset therefrom, to occupy the position between the first and second keys; and type-bars set close together and having the 40 same order as the levers and connected thereto.

13. In a typewriting machine, the combination of two levers placed side by side, keys offset in opposite directions from said levers, 45 one key immediately behind the other, a third lever at one side of said levers and having a key offset therefrom, to occupy the position between the first and second keys, the third key being offset materially more than 50 either of the other keys; and type-bars set close together and having the same order as the levers and connected thereto.

14. In a typewriting machine, the combination of two levers placed side by side, keys 55 offset in opposite directions from said levers, one key immediately behind the other, a third lever at one side of said levers and having a key offset therefrom, to occupy the position between the first and second keys, a 60 key-bank intervening between the third key

and the first two keys; and type-bars set close together and having the same order as the levers and connected thereto.

15. In a typewriting machine, the combination of a system of keys arranged in banks 65 in symmetrical order, a system of key levers bearing said keys on their ends, said key levers being of different lengths to correspond with the different banks of keys and being arranged in disordered echelon, and the 70 keys being variously offset to different extents some to one side and some to the other of their levers, to make the transverse order of the keys substantially different from the transverse order of the levers, and a system 75 of type-bars lying close together and having the same order as the levers.

16. In a typewriting machine, the combination with a system of key levers, of a system of keys mounted thereon, the center of 80 each key being midway between the adjoining levers, some of the keys being offset to the left and others to the right from said adjoining levers, and some of the keys being attached to levers at the immediate left of 85 said adjoining levers, and other keys being attached to levers at the immediate right of said adjoining levers, to make the transverse order of the levers different from that of the keys, and bring infrequently used levers between levers which are frequently used 90 consecutively, and a system of type-bars lying close together and having the same order as the levers.

17. The combination of three levers having 95 keys offset to the left, a fourth lever having a key offset to the right, and a fifth lever having a key offset to the left sufficiently to bring it between the third and fourth keys, and type-bars set close together and having 100 the same order as the levers and connected thereto.

18. A keyboard in which each key overhangs four levers, the center of the key being about midway of the space of the middle levers, to make the order of the keys different from the order of the levers, and type-bars mounted close together and having the same order as said levers, and connected thereto. 105

19. In a typewriter, the combination of 110 key-levers, keys on said levers offset in such a manner that the order of the keys differs from the order of the levers, pivoted type-bars lying close together in the order of said levers, and means for enabling said levers to 115 operate said type-bars.
